UNDERARM GARMENT SHIELD AND CLIP
THEREFOR

Arthur Richard Seaquist, Chicago, Ill.

Application April 30, 1947, Serial No. 744,842

11 Claims. (Cl. 2—56)

1

This invention relates to underarm garment shields, more particularly to clips for supporting disposable garment shields in proper protective relation with respect to the armhole of a garment and the invention has for an object the provision of simple, inexpensive and reliable devices of this character.

The damage, such as discoloration, staining and other unpleasant effects, that may result to garments from underarm perspiration unless proper precautions and remedial measures are taken is well known and the present invention provides a simple and readily usable underarm shield that may be quickly and securely applied to the armholes of a garment to protect the garment during use. In accordance with this invention, a light wire clip is provided including a supporting portion shaped to span the armhole of the garment for supporting in protecting position a suitably folded shield member. The supporting portion of the clip is provided at each end with resilient means for securely clamping the shield member while permitting ready removal of the shield member from the clip for disposal and replacement and means are likewise provided at each end of the supporting portion of the clip for securing the clip to the garment at opposite sides of the armhole with the shield member in proper shielding position and for permitting ready removal of the clip from the garment to facilitate disposal and replacement of the shield member.

It is a particular object of this invention to provide a light, shield-supporting clip for underarm use that will not cause discomfort to the wearer of the garment.

It is another object of this invention to provide a clip of this character that securely clamps the garment and does not become displaced during use.

A still further object is to provide a clip of the character indicated which will not detract from the appearance of the garment, which may be readily applied thereto and removed therefrom and which securely holds the shield member against displacement.

For a more complete understanding of the invention, reference should now be had to the drawings, in which

Fig. 1 is an elevational view of a shield-supporting clip embodying the present invention;

Fig. 2 is an end elevational view of the clip shown in Fig. 1;

Fig. 3 is a top plan view of the clip shown in Figs. 1 and 2;

2

Fig. 4 is a perspective view of an underarm shield embodying the present invention and illustrating the application of a folded shield member to the supporting clip of Fig. 1;

5 Fig. 5 is a fragmentary elevational view partly in section showing the underarm shield of Fig. 4 applied to the armhole of the garment, the section through the shield being taken along the line 5—5 of Fig. 4;

10 Fig. 6 is a fragmentary elevational view showing one end of another form of shield-supporting clip embodying the present invention;

Fig. 7 is the end elevational view of the form of clip shown in Fig. 6; and

15 Fig. 8 is a fragmentary elevational view showing one end of still another form of clip embodying the present invention.

Referring now to Figs. 1 to 5 of the drawings, the invention is shown as embodied in an underarm shield comprising a folded shield member 10 and a supporting clip 11 which serves to securely position the shield member 10 and which may be readily attached to and detached from the armhole of a garment so as to support the shield member 10 in proper shielding position. Although the shield member 10 has been illustrated as comprising a pair of crescent-shaped leaves joined along their concave arcuate edge so as to provide a two-ply folded structure, it will be understood, of course, that the shield member may be of any desired shape. Likewise the shield member 10, although preferably formed of absorbent paper, may be formed of any suitable material and may be chemically treated with deodorizing or other compounds if desired.

As shown, the shield supporting clip 11 which is preferably formed of fine resilient wire includes an arcuately formed body portion 12 adapted to span the armhole of the garment and 40 to be engaged by the shield member 10. At each end of the clip the body portion 12 terminates in a double return bend disposed in the plane of the arcuate portion 12 so as to provide a first return bend portion 13 and a second return bend portion 14, the bend portion 13 extending inwardly from the end of the arcuate portion 12 and the bend portion 14 extending outwardly beyond the end of the portion 12 at its outer end. The bend portion 14 terminates in a plurality of loops 15 and 16, the loop 15 being disposed partially in the plane of the arcuate portion 12 and the loop 16 being offset in side by side relation with the loop 15.

As heretofore indicated, the clip 11 is formed 55 from resilient wire and the first return bend 13 is

so formed that the end thereof resiliently engages the arcuate portion 12 at the point indicated by the reference numeral 17 in Fig. 1. Thus, a resilient clamping means is provided for gripping the shield member 10 at points inwardly from opposite edges thereof when the shield member 10 is positioned on the clip 11 as shown in Figs. 4 and 5. As shown, the upper portions of the side by side loops 15 and 16 are spaced apart and connected by a member 18 which forms a continuation of each of the loops and the loops are tilted so that the bottom portions of the loops engage each other as indicated by the reference numeral 19 in Fig. 2. The resiliency of the wire from which the loops 15 and 16 and the connecting member 18 are formed is such that the bottom portions of the loops may be spread apart to permit the insertion therebetween of a portion of the garment and thus the loops serve resiliently to clamp the garment so as to support the shield in proper position.

In Fig. 5, the underarm shield is shown as applied to the armhole of a garment comprising a body portion 20 and a sleeve portion 21 which are joined in the usual fashion by a seam 22 and, in order to support the shield, the seam 22 at opposite sides of the armhole is inserted between the loops 15 and 16 at the opposite ends of the clip so that the seam is resiliently gripped at the point indicated by the reference numeral 19 in Fig. 5. With the clip thus secured to the armhole of the garment it will be observed that the downwardly extending leaves of the shield member 10 straddle the lower portion of the armhole seam, one leaf being within the sleeve and the other within the body portion of the garment. Thus the shield member 10 overlies and protects the portion of the garment normally exposed to underarm perspiration and it will be observed that after the shield has been used it is necessary only to remove the clip from the armhole and withdraw the shield element 10 from the clip 11, whereupon a fresh shield element may be inserted into the resilient clamping means provided by the return bend portions 13. The underarm shields embodying the present invention may thus be readily applied and removed and will not, while in use, distort the garment so as to cause an unsightly appearance, nor will they cause discomfort to the user.

In Figs. 6 and 7 a somewhat different form of clip is shown which may be used in the same manner as the clip 11 in conjunction with the shield element 10. In the embodiment of Figs. 6 and 7 two complementary wire members are employed, each of which includes an arcuate portion 12a, and a double return bend consisting of portions 13a and 14a, but in this embodiment of the invention the portions 14a terminate in arms 23 provided with half loops 24 and diverging end portions 25. When the two wire members are placed in side by side relation and spot-welded together at suitable points, for example, points 26 and 27, it will be observed that a clip is provided in which the return bend portions 13a cooperate with the arcuate portions 12a to form resilient clamping means for the shield member 10, and the arms 23 which extend from the return bend portion 14a provide a resilient clamping means adapted to grip a portion of the garment when this garment portion is inserted between the diverging end portions 25, the gripping action being accomplished at the point 30 (Fig. 7) which constitutes the intersection of the half loops 24 and the diverging end portions 25.

In the embodiment of the invention shown in Fig. 8, the clip comprises an arcuate portion 12b, return bend portions 13b and 14b similar to portions 12, 13 and 14 of the embodiment shown in Fig. 1, but the return bend portion 14b in this embodiment terminates in a downwardly extending arm or pin 31 by means of which the clip may be pinned rather than resiliently clamped to the garment.

10 In order to provide a maximum gripping action, clips embodying the present invention are preferably formed from roughened or burred wire, but if desired, clips may be formed from smooth wire and suitable serrations or other friction producing surfaces may be formed at the gripping points 17 and 19 so that both the shield member 10 and the garment will be securely clamped or gripped.

15 While I have shown particular embodiments of my invention, it will be understood, of course, that I do not wish to be limited thereto since many modifications may be made, and I, therefore, contemplate by the appended claims to cover any such modifications as fall within the true spirit and scope of my invention.

20 Having thus described my invention, what I claim and desire to secure by Letters Patent is:

25 1. A garment shield for underarm use comprising an absorbent member folded to provide a pair of downwardly extending leaves, an elongate supporting member extending along the fold between said leaves, resilient means at each end of said supporting member for clamping said absorbent member thereto, and means disposed outwardly of said absorbent member for securing said supporting member to the garment.

30 2. A garment shield for underarm use comprising an absorbent member folded to provide a pair of downwardly extending leaves, a wire extending between said leaves along said fold, resilient means at each end of said wire extending inwardly over said absorbent member to clamp said absorbent member to said wire at points adjacent the edges of said member, and means disposed outwardly of said clamping means for securing said wire to the garment.

35 3. A garment shield for underarm use comprising an absorbent member folded to provide a pair of downwardly extending leaves, a wire extending between said leaves along said fold, said wire having a first return-bend portion at each end extending inwardly over the edges of said absorbent member to clamp said member to said wire, and having a second return-bend portion at each end extending outwardly from said first return-bend portions beyond the edges of said absorbent member, and means carried by said second return-bend portions for securing said wire to the garment.

40 4. A garment shield for underarm use comprising an absorbent member folded to provide a pair of downwardly extending leaves, a wire extending between said leaves along said fold, said wire having a first return-bend portion at each end extending inwardly over the edges of said absorbent member to clamp said member to said wire, and having a second return-bend portion at each end extending outwardly from said first return-bend portions beyond the edges of said absorbent member, said second return-bend portions terminating in resilient clamping means for securing said wire to the garment.

45 5. A garment shield for underarm use comprising an absorbent member folded to provide a pair of downwardly extending leaves, a wire extending between said leaves along said fold, said wire hav-

ing a first return-bend portion at each end extending inwardly over the edges of said absorbent member to clamp said member to said wire, and having a second return-bend portion at each end extending outwardly from said first return-bend portions beyond the edges of said absorbent member, said second return-bend portions each terminating in a plurality of loops arranged in side-by-side relation to form resilient clamps for securing the opposite ends of said wire to the garment.

6. A garment shield for underarm use comprising an absorbent member shaped to provide a pair of downwardly extending leaves joined together along arcuate upper edges, an arcuate wire extending between said leaves and engaging the joint between said leaves to support said member, resilient means at each end of said wire extending inwardly over said absorbent member to clamp said member to said wire, and means disposed outwardly of said clamping means for securing the ends of said wire to the garment.

7. A garment shield for underarm use comprising an absorbent member shaped to provide a pair of substantially crescent-shaped leaves joined together along the concave edges thereof, an arcuate wire support extending longitudinally between said leaves and engaging the joint therebetween to support said member, said wire including a return-bend portion at each end extending inwardly over said absorbent member to clamp said member to said wire, and means disposed outwardly of the edges of said absorbent member for securing the opposite ends of said wire to the garment.

8. A garment shield for underarm use comprising an absorbent member shaped to provide a pair of substantially crescent-shaped leaves joined together along the concave edges thereof, an arcuate wire support extending longitudinally between said leaves and engaging the joint therebetween to support said member, said wire including a return-bend portion at each end extending inwardly over said absorbent member to clamp said member to said wire, said wire including second return-bend portions extending from said first return-bend portions and each terminating outwardly of the edges of said mem-

ber in a plurality of side-by-side loops for resiliently gripping portions of the garment to secure said wire thereto.

9. A one-piece wire clip for supporting an under arm garment shield comprising an arcuate section for spanning the armhole of a garment, which section terminates at the opposed ends thereof in a double reverse bend engaging said arcuate section inwardly of the ends thereof to form 10 a first clamping means and having a second clamping means extending outwardly of said ends for engaging a garment.

10. A one-piece wire clip for supporting an underarm garment shield comprising an arcuate section for spanning the armhole of a garment, which section terminates at the opposed ends thereof in a double reverse bend engaging said arcuate section inwardly of the ends thereof to form 15 a first clamping means and having a second clamping means extending outwardly of said ends for engaging a garment.

11. A clip for supporting an underarm garment shield comprising an elongate member for spanning the armhole of the garment, means at each 20 end of said member for resiliently clamping a removable shield, said means being integral with said member and extending back over and substantially in alignment with said member, and additional means at each end of said member for 25 engaging the garment at opposite sides of the armhole to secure said member to the garment.
